(57) **CLAIM**

The ornamental design for body armor, as shown and described.

DESCRIPTION

FIG. 1 is a perspective view of a first example of the body armor;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second example of the body armor;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof; and,

FIG. 15 is a front environmental view showing the body armor of the figures above partially inserted into a front side of a vest or carrier worn by a female user.

Broken lines shown in the figures form no part of the claimed design.

1 Claim, 11 Drawing Sheets
